UNITED STATES PATENT OFFICE

ARVID LINDBERG, OF LIMA, OHIO

SMOKE SHADE FOR FIREPLACES

Application filed February 27, 1931. Serial No. 518,859.

The present invention relates to a smoke shade designed for use on fire places and has for its object to provide means for use in conjunction with an open fire place to prevent the smoke from coming into the room or the like when the draft from the flue is acting poorly particularly when the flue is cold at the start of the fire in the fire place.

Another very important object of the invention resides in the provision of a smoke shade which is simple in its construction, inexpensive to manufacture and install, easy to manipulate, compact and convenient in its arrangement of parts, thoroughly efficient and reliable in use and operation, and otherwise well adapted to the purpose for which it is designed.

In the drawings:

Figure 1 is a front elevation of a fire place showing my shade in place.

Figure 2 is a horizontal section therethrough.

Figure 3 is a vertical section therethrough showing the shade in closed position.

Figure 4 is a similar view showing the shade in open position.

Figure 5 is a sectional view taken substantially on the line 5-5 of Figure 4.

Figure 6 is a perspective view of one of the segmental frames.

Figure 7 is a detail perspective view showing one of the coil guides for the shade, and

Figure 8 is a perspective view of one of the mounting brackets.

Referring to the drawings in detail it will be seen that the numeral 5 denotes a fire place of any ordinary or preferred construction and against the side walls in the fire place I position hollow walls 6 across the top of which is disposed a casing 7 the rear of which is closed and the front of which is open.

This casing is anchored in place by arms 8 connected to L-shaped brackets 9 fixed to the fire place as at 10 and having slots 11 to receive bolts 12 in the arm 8 thus accommodating fire places of different sizes. Segmental frames 14 include arcuate portions *a* having flanges *b* and radial sections *c* of angular construction with bearings 15 which are rockable on pins 16 in the walls 6 so that

these frames may be swung from position shown in Figure 3 to position shown in Figure 4 and vice versa.

One end of each frame is formed with a hook 17. Plates 18 are in the frames to close the same and these plates may be constructed of mica or any other suitable material.

Numerical 19 denotes a shade which may be constructed of any suitable flexible sheet material. A bead 20 is provided on one end of the shade and is fixed in the crotches of the hooks 17.

The shade is adapted to be disposed in the casing and when fully disposed therein as is shown in Figure 4 to form a coil portion by means of coil guides 21 adjacent the rear of the casing and formed on the side walls thereof. The bottom of the casing adjacent the side is slotted as at 22 so as to permit entrance of a portion of the section *a* and also a portion of the section *c* as is illustrated to advantage in Figure 4.

A suitable handle 23 is provided on the bead 20. A door 25 is hingedly mounted as at 26 on the casing to close the front end thereof when the shade is in the open position illustrated in Figure 4. This door may be swung upwardly and by grasping the handle 23 the shade is pulled outwardly to the position shown in Figure 3 at which time the side edges of a portion of the shade out of the casing rest on the sections *a* to the inside of their flanges *b*.

When starting a fire in the fireplace the shade should be placed in its closed position shown in Figure 3 and this will prevent the smoke from coming out into the room until the fire place heats up sufficiently to provide a proper draft and of course the draft will draw out the smoke from the hood like formation provided by the shade in closed position and then the shade may be moved to its open position shown in Figure 4 by pulling upwardly on the handle 23 as will be quite apparent.

The flexible sheet 6 should be stiffened in any suitable manner to prevent it from buckling when the hood is raised from the position shown in Figure 3 to that shown in Figure 4 though if the sheet should buckle it

could be pressed upon by one of the hands of the operator when the device is being raised to prevent it from buckling. The door 25 also tends to prevent the sheet from buckling as it rests on the hood structure and acts as guiding means for the sheet as shown in Figure 3.

It is thought that the construction, utility, operation and advantages of this invention 10 will be now quite apparent to those skilled in this art without a more detailed description thereof.

The present embodiment of the invention has been described in considerable detail 15 merely for the purposes of exemplification since in actual practice it attains the features of advantage enumerated as desirable in the statement of the invention and the above description.

20 It is apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. An apparatus of the class described comprising a pair of hollow side walls, a casing 30 across the top of the side walls and having an open front, a shade adapted to be pulled from and pushed into the casing, a pair of frames having arcuate sections, means for rockably mounting the frames in the side 35 walls, said casing having slots to receive portions of the frames, said shade having one end fixed to the frame so that the side edges thereof may rest on the arcuate sections of the frames when the frames are swung outwardly from the side walls.

40 2. An apparatus of the class described comprising a pair of hollow side walls, a casing across the top of the side walls and having an open front, a shade adapted to be pulled 45 from and pushed into the casing, a pair of frames having arcuate sections, means for rockably mounting the frames in the side walls, said casing having slots to receive portions of the frames, said shade having one end 50 fixed to the frame so that the side edges thereof may rest on the arcuate sections of the frames when the frames are swung outwardly from the side walls, coil guides in the sides of the frames to coil portions of the shade 55 when pushed into the casing.

In testimony whereof I affix my signature.
ARVID LINDBERG.
